R. J. TURNER,
AUTOMATIC CARTRIDGE MAGAZINE,
APPLICATION FILED JUNE 21, 1920.

1,368,375.

Patented Feb. 15, 1921.

UNITED STATES PATENT OFFICE.

RUSSELL J. TURNER, OF YOUNGSTOWN, OHIO, ASSIGNOR OF ONE-HALF TO CHARLES A. HARPMAN, OF YOUNGSTOWN, OHIO.

AUTOMATIC CARTRIDGE-MAGAZINE.

1,368,375.

Specification of Letters Patent. Patented Feb. 15, 1921.

Application filed June 21, 1920. Serial No. 390,503.

To all whom it may concern:

Be it known that I, RUSSELL J. TURNER, citizen of the United States of America, residing at Youngstown, in the county of Mahoning and State of Ohio, have invented certain new and useful Improvements in Automatic Cartridge-Magazines, of which the following is a specification.

This invention relates to automatic cartridge magazines for firearms, and has for its principal purpose the providing of a magazine securely inclosed within a casing, thereby freeing the magazine from humidity, dust, sand and dirt to which the ordinary magazine is exposed.

Another object of the invention is to provide a flexible push rod actuated by being attached to a slidable clasp mounted upon a spring actuated arm.

A still further object is to provide a straight outlet end for the emitting of cartridges, this part being an extension of spiral wound portion having an incased channel for cartridges and a spring actuated arm energizing a flexible push rod.

The invention also consists in the further novel constructions and combinations of parts hereinafter more fully described and claimed and illustrated in the accompanying drawings, showing the preferred form of my invention and in which:

Figure 1 is a vertical top plan view partly in section.

Fig. 2 is a vertical side view partly in section.

By referring to Fig. 1, it will be seen that I have provided an outlet portion 1 provided with a spiral wound extension 2. Within the casing 3 I have provided a spiral partition 4 forming a spiral channel 5 in which the cartridges 6 are held. The cartridges 6 are fed into the magazine at the opening 7. Fig. 1 shows the magazine filled, with the exception of the open channel portion 8. As the cartridges are fed out at the opening

7 the spring actuated arm 9 presses the flexible push rod 10, which is secured to the slidable clasp 11, so that the cradle 12 located at the end of the flexible push rod 10 pushes the cartridges up to the opening 7. When 50 the cartridges have been fed out until they reach the straight outlet part 1 the flexible push rod 10 straightens in order to push the last cartridge into the opening 7.

By referring to Fig. 2 it will be seen that 55 I have provided a downwardly extended arm 13 which is secured to the slidable clasp 11. At the end of this downwardly extended arm 13 the flexible push rod 10 is pivoted by means of a pin 14. A spiral spring 15 60 is secured at one end to a bearing 16, which is firmly secured to a bridge member 17 secured within the inner portion of the spiral partition 4. It will also be seen that the spring actuated arm 9 is provided with a 65 downwardly extended axle 18 which turns within the bearing 16.

What I claim is:

In a device of the class described a cartridge channel straight at the upper end, 70 which is connected with the breech of the gun, and spiral in form at the lower end, a partition forming a cartridge channel, a casing inclosing the entire cartridge channel, a spring influenced axle revolvably mounted 75 within said casing, a bridge member supporting a bearing carrying said axle, an arm portion of said axle, a slidable clasp on said arm, a downwardly extended portion, a flexible push rod attached to said downwardly extended portion of arm, a cradle member secured to outer end of said flexible push rod, substantially as described for the purpose set forth.

In testimony whereof I affix my signature. 85

RUSSELL J. TURNER.

Witnesses:

C. A. HARPMAN,
D. A. FRAMPTON.
